ATTORNEY

UNITED STATES PATENT OFFICE.

JESSE OPPENHEIM, OF NEW YORK, N. Y.

HAIR PIECE.

Application filed January 4, 1928. Serial No. 244,406.

This invention relates to hair pieces for women's head dress and more particularly is directed to a hair piece for use on bobbed coiffures.

5 One object of the invention is to provide a hair piece of improved construction which shall be easily and positively secured in position to snugly fit over short hair or thinned regions of a bobbed head coiffure and which 10 may readily be incorporated with the natural hair to simulate a desired long hair coiffure.

Another object of the invention is to provide in a hair piece of the character described, an attachment device of improved construction 15 for engaging with the short natural hair of the wearer.

A further object of the invention is to provide an improved hair piece of the character described, comprising few and simple parts, 20 which shall be cheap to manufacture, easy to apply and remove, adapted to form various styles of coiffure, and practical and efficient to a high degree in use.

Other objects of this invention will in part 25 be obvious, and in part hereinafter pointed out.

The invention accordingly consists in the features of construction, combinations of elements, and arrangement of parts which will 30 be exemplified in the construction hereinafter described, and of which the scope of application will be indicated in the following claims.

In the accompanying drawing, in which is shown one of the various possible illustrative 35 embodiments of this invention.

Fig. 1 is a view showing a hair piece embodying the invention applied in a coiffure on the rear side of the wearer's head, over a short, natural hair region.

40 Fig. 2 is a fragmentary, perspective view of the improved hair piece removed from the wearer's head.

Fig. 3 is a cross-sectional view taken on lines 3—3 in Fig. 1, and

45 Figs. 4 and 5 are bottom plan views of the novel attaching device for the improved hair piece showing the clamping means thereof in open and closed positions, respectively.

Referring in detail to the drawing, 10 denotes a hair piece embodying the invention which is particularly adapted to be incorporated in women's coiffure of the prevailing popular bobbed hair style to extend over and cover the regions of cut or thinned, natural, 50 short hair 11^a at the rear of the head 11, as

shown in Fig. 1, for giving the appearance of natural, long hair coiffure.

The improved head dress piece 10 is seen to comprise an attachment device 12 of novel construction, to which is secured a suitable tuft of hair 13. The hair tuft 13 may be constructed in any well understood manner with the individual hairs secured in an anchoring edge 13^a to form a puff, curl, plait, switch, or braid, of a texture and color to match the natural hair of the wearer for incorporating in the coiffure to cover the region of the natural, short hair 11^a. The attachment devices 12 may comprise a comb member 12^a having teeth 12^b and a back edge 12^c, which is extended, as at 12^d, to carry a suitable connection 14 for pivoting a clamping member 15. The comb member 12^a and clamping member 15 may be formed of any suitable material, metallic or non-metallic, 75 but is preferably made of celluloid, hard rubber, wood, fibre, casine, or phenol-condensate products, the back edge portion 12^c being provided with perforation 12^e, wherethrough stitches 16 pass for flexibly securing the edge 13^a of the tuft to the portion 12^c, as is clearly shown in Figs. 2 and 3.

The tuft of hair 13 is preferably mounted to extend from said back edge portion 12^c, and may have an upper folded portion 13^b spaced from said device 12 for retaining the tuft to simulate draped, natural hair and to position the tuft to extend over and conceal said attachment device.

The shape and position of the folded portion 13^b may be given a limited adjustment with respect to the device 12 by providing a bendable member 17 between the attachment device 12 and the tuft 13. As here shown, said member 17 comprises a wire reinforced ribbon, secured to extend along the anchoring edge 13^a of the tuft, the free ends of which are bendably adjustable within the folded portion 13^b, and may engage the incurled free end 13^c of the tuft 13 as shown in Fig. 3.

The clamping member 15 is preferably made of resilient material folded along its length and provided with an elongated slot 15^a. Said member 15 has one end 15^b thereof mounted on connection 14, and is adapted to swing with relation to said comb member, so as to extend along both sides and embrace the back edge portion 12^c after the teeth 12^b have passed through the slot 15^a. The folded portion 15^c of the material of

member 15 adjacent the end 15^b serves to limit the swinging movement of the member 15, and the folded portion 15^a of said material at the end opposite portion 15^c forms a handle 5 for conveniently manipulating the clamping member 15.

In order to assure positive clamping effect of the member 15 with said back edge portion 12^c, the slot 15^a is made relatively narrower 10 adjacent the handle portion 15^a of the member 15 than at the other end 15^c, so that the spring action of said member 15 on both sides of said portion 12^c is greatly increased, as is clearly shown in Fig. 6.

15 In using the improved hair piece 10, it may be applied to a bobbed head to cover the relatively short or thinned regions of the wearer's head and incorporated in the coiffure to simulate natural, long hair. This application is easily and simply accomplished by 20 positioning the device over a desired region and inserting the comb member 12^a into the underlying short hair 11^a. On swinging the clamping member 15 into its embracing 25 position, the short hair 11^a is looped about the back portion 12^c of the comb as shown at 11^b in Fig. 3, thus snugly securing the device 12 to the head of the wearer. By reason of the transversely strong spring action at the 30 narrow end 15^a of the clamp member, the latter will now be held securely in position thus preventing possible opening up of the clamp. The tuft 13 may now be dressed about the wearer's head in any desired artistic manner 35 to merge with the real hair, thus concealing the device 12 and giving the bobbed head the appearance of a coiffure of natural, long hair. The folded portion 13^b provided in the tuft 13 with the adjustably bendable member 17, not only aids in concealing the 40 attaching device 12, but also serves to form the tuft 13 into shapes that simulate contours of desirable long, natural hair coiffures.

To remove the piece 10, the device 12 is 45 simply unclamped from the short hair 11^a.

To further insure positive clamping action any of the contacting or gripping surfaces of the clamp member 15 may be corrugated or provided with projecting portions.

50 It will thus be seen that there is provided a device in which the several objects of this invention are achieved and which is well adapted to meet the conditions of practical use.

55 As various possible embodiments might be made of the above invention, and as various changes might be made in the embodiment above set forth, it is to be understood that all matter herein set forth or shown in the accompanying drawing is to be interpreted as 60 illustrative and not in a limiting sense.

Having thus described my invention, I claim as new and desire to secure by Letters Patent:

65 1. A hair piece for covering short, natural

hair regions of a coiffure, comprising an attachment means for engaging with the short hair of said region, and a tuft of hair carried by said means, said tuft having a fold portion extending from one side of said means and folded over the top and opposite side of said means for retaining said tuft in form to simulate the natural hair, and to completely conceal said attachment means.

2. A hair piece for covering short, natural regions of a coiffure, comprising an attachment means for engaging with said short hair, a tuft of hair mounted to extend beyond said means, said tuft having a fold for spacing said means inwardly with respect to the fold to conceal said means and to retain said tuft in form to simulate the natural hair, and means positioned between said attachment means and tuft for retaining the tuft in a desired shape.

3. In a hair piece of the character described, an attachment means comprising a comb having a back portion and teeth extending from said back portion, and a member having a slot for receiving said teeth, whereby short hair may be releasably held looped between the teeth by said back portion and said member.

4. In a hair dress piece, means for attaching a tuft of hair to short, natural hair of a coiffure comprising a comb, and a member adapted to extend on opposite sides of said comb for anchoring said attaching means to said short hair in a loop about the comb member.

5. In a hair dress piece, means for attaching a tuft of hair to short, natural hair of a coiffure comprising a comb, and a member adapted to extend on opposite sides of said comb for anchoring said attaching means to said short hair in a loop about the comb member, said member forming a flat spring clamping structure adapted to embrace said comb.

6. In a hair piece of the character described, an attachment means comprising a comb having a back portion and teeth extending from said back portion, and a member having a slot for receiving said teeth, said member being resilient, and said slot being of non-uniform width and adapted to clampingly engage hair looped about said back portion.

7. In a hair piece, a comb having a back portion and teeth extending from said portion, means on said portion for mounting a tuft of hair, an extension on said portion, and a member pivoted on said extension, said member having a slot to permit passage of said teeth therethrough on swinging said member, whereby short hair may be releasably secured in a loop by said comb and member.

8. In a hair piece, a comb having a back portion, and teeth extending from said por-

tion, means on said portion for mounting a tuft of hair, an extension on said portion, and a member of resilient material pivoted on said extension, said member having a slot 5 to permit passage of said teeth therethrough on swinging said member, whereby short hair may be releasably secured in a loop by said comb and member.

9. A hair piece for covering short natural 10 hair regions of a wearer comprising a tuft of false hair, and an attachment device concealed within said tuft for mounting the latter over said regions, said device including toothed means for looping the natural 15 hair about the device and means having an opening for receiving said toothed means to clamp said looped hair to said toothed means.

10. The combination of a comb having 20 teeth and clamping means pivoted at one end only of said comb comprising a resilient member having a slot wherethrough said

teeth pass upon swinging of the comb member about said pivot into clamping position, the free end of said clamping member being of narrowed cross-section for effectively gripping the comb. 25

11. An article of hair dress comprising an attaching member having a body portion and teeth for receiving the wearer's hair 30 therethrough, and means for clamping the hair against the opposite sides of said body portion.

12. In a hair piece adapted to cover the short natural hair of a wearer, the combination of a tuft of false hair simulating the natural hair, and means for mounting said tuft on the natural hair, said mounting means including a toothed element engaging the short natural hair in looped relation, and 35 40 means for clamping said looped hair to said toothed element.

In testimony whereof I affix my signature.
JESSE OPPENHEIM.
